UNITED STATES PATENT OFFICE.

EDWARD PAVELKA, OF NEW YORK, N. Y., ASSIGNOR TO GILLIS & GEOGHEGAN, OF NEW YORK, N. Y., A FIRM.

BRAKE MECHANISM FOR HOISTING APPARATUS.

1,163,169.

Specification of Letters Patent.

Patented Dec. 7, 1915.

Application filed August 25, 1914. Serial No. 858,452.

To all whom it may concern:

Be it known that I, EDWARD PAVELKA, a citizen of the United States, residing in the city of New York, borough of Bronx, in the 5 county of Bronx and State of New York, have invented a certain new and useful Improvement in Brake Mechanism for Hoisting Apparatus, of which the following is a specification.

10 The invention relates to hand operated hoisting apparatus designed for lifting comparatively light loads, and is based upon Letters Patent to John A. Kearney, dated May 19, 1914, No. 1,097,233.

15 The object of the invention is to provide means for reliably locking the drive-shaft while the load is controlled by the brake alone and thus prevent the accidental re-engagement of the drive-shaft with the 20 winding-shaft and eliminate the danger of idle revolutions of the crank during the lowering operation.

Another object is to provide simple means 25 conveniently located for holding the drive-shaft in engagement with the winding-shaft and preventing accidental release during the hoisting operation.

The invention consists in certain details 30 of construction and arrangement by which the above objects are attained, to be herein-after described and claimed.

The accompanying drawings form a part 35 of this specification and show the invention as it has been carried out in practice.

Figure 1 is a side elevation of the improved hoisting apparatus and a portion of the telescopic standard on which it is mounted. Fig. 2 is a plan view of the mechanism on a larger scale. Fig. 3 is a corresponding 40 side elevation of a portion, partly in vertical section, the plane of section being indicated by the broken line 3—3 in Fig. 2. Fig. 4 is an elevation of a portion showing the locking means, certain parts being in 45 vertical section. Fig. 5 is a front view of the locking tooth alone, on a still larger scale.

Similar letters of reference indicate the same parts in all the figures.

50 A is a standard supporting a head B mounted upon the upper end thereof and forming part of an overhanging frame having two outwardly extended arms B¹ B² in which are mounted two parallel horizontal shafts C and D, the former a relatively fixed

winding-shaft carried at the outer ends of the arms, and the latter an axially slideable drive-shaft mounted between the winding-shaft and head B. On the winding-shaft C is a gearwheel C¹, a winding-drum or spool C² on which the hoisting cable M is wound, and a brake-drum C³, all fixed on the shaft C and revolving therewith. The drive-shaft D carries a pinion D¹ fixed thereon adapted to mesh with the gearwheel C¹, and is squared at one end to receive the crank F by which it may be revolved and correspondingly rotate the winding-shaft. The shaft D is mounted to slide axially under certain conditions and is extended outwardly at the end opposite to the crank to permit such endwise movement without escaping from its bearings in the arms B¹ B². Partially encircling the brake-drum is a 60 brake-band E attached to a brake-lever G in such manner as to tighten the band when the lever is raised and thus grasp the brake-drum. Fixed on the shaft D is a cone D² lying normally adjacent to the brake-lever G which has an arm G¹ extending beneath the cone to a high point on the latter, and as the lever is raised to apply the brake the arm G¹ acts on the inclined surface of the cone and forces the latter with the shaft D to move axially thus sliding the teeth of the pinion D¹ on those of the gearwheel C¹ while still in mesh therewith until at the point at which the brake friction is sufficient to hold the load, the teeth of the pinion are disengaged completely from the gearwheel and the suspended load is held by the brake alone. In this condition the load may be lowered at any desired speed and under full control by relaxing or varying the upward 70 pull on the brake-lever G. When another load is to be hoisted the drive-shaft D is thrust back to its original position by hand with its pinion in mesh with the gearwheel C¹. In the hoisting operation the load is held against descent by a pawl H pivotally mounted on the frame at h and adapted to ride the teeth of the pinion D¹ when the latter is rotated in the direction to hoist, and to engage the teeth and hold the pinion against rotation in the direction to lower. The nose of the pawl is of such width as to maintain its engagement with the pinion even when the latter is moved axially out of mesh as above described.

To insure against accidental or uninten-

tional endwise movement of the shaft D during the hoisting operation a latch J is provided, pivoted on the exterior of the arm B² at j and having a curved arm J¹ partially encircling the shaft and having a portion J² adapted to engage in an annular groove d in such shaft. The latch is conveniently located adjacent the brake-lever G and is raised to free the shaft before the application of the brake by depressing the thumb-plate J³ thereon, and the lifting movement is limited by the tail J⁴ striking the head of the bolt G² on which the brake-lever is pivoted, thus holding the latch supported idly on the end of the shaft D during the shifting movement and in position to fall by gravity into engagement with the groove d when the latter is again presented thereto.

It has been found desirable to provide means for preventing the partial reengagement of the pinion and gearwheel during the lowering operation in order to avoid danger to the operator by the accidental revolutions of the crank F liable to be thus induced. For this purpose a pin or tooth L is secured to the inner face of the arm B¹ in position to be engaged between adjacent teeth on the pinion D¹ when the latter and its shaft D are moved axially to disengage the pinion and gearwheel, and thus lock the shaft D against rotation in either direction. The tooth L is shaped to match the space between adjacent teeth on the pinion and extends close to the side face of the latter so that its engagement follows immediately upon the endwise movement of the shaft, and the mechanism is locked against rotation until such movement is completed and the load held by the brake. When the pinion is freed from the gearwheel it is still locked and the drive-shaft and crank held against rotation until the reengagement of the pinion and gearwheel is again fully established ready for another hoisting operation. The tooth L is shown as having a base L¹ secured to the inner face of the arm B¹ but it will be understood it may be otherwise shaped and located. The form of the latch J may be varied and any suitable stop supplied therefor in place of the bolt G².

I claim:—

1. In a hoisting apparatus, a winding-shaft, a gearwheel and winding-drum fixed thereon, a brake device on said shaft, a lever for operating such brake device, an axially slideable drive-shaft, a pinion fixed on said drive-shaft and arranged to mesh with said gearwheel, a cone fixed on said drive-shaft, and means carried by said lever for engaging said cone and moving said drive-shaft axially, thereby sliding said pinion out of mesh with said gearwheel in the act of applying the brake, and fixed means arranged to engage said pinion immediately after the

initiation of such axial movement and hold said pinion and drive-shaft against rotation.

2. In a hoisting apparatus, a winding-shaft, a gearwheel and winding-drum fixed thereon, a brake device on said shaft, a lever for operating such brake device, an axially slideable drive-shaft, a pinion fixed on said drive-shaft and arranged to mesh with said gearwheel, a cone fixed on said drive-shaft, and means carried by said lever for engaging said cone and moving said drive-shaft axially, thereby sliding said pinion out of mesh with said gearwheel in the act of applying the brake, and a tooth fixedly mounted relatively to such pinion and arranged to be received between adjacent gear teeth on the latter immediately after the initiation of such axial movement and hold said pinion and drive-shaft against rotation. 85

3. In a hoisting apparatus, a winding-shaft, a gearwheel and winding-drum fixed thereon, a brake device on said shaft, a lever for operating such brake device, an axially slideable drive-shaft having an annular groove therein, a pinion fixed on said drive-shaft and arranged to mesh with said gearwheel, a cone fixed on said drive-shaft, and means carried by said lever for engaging said cone and moving said drive-shaft axially, thereby sliding said pinion out of mesh with said gearwheel in the act of applying the brake, a tooth fixedly mounted relatively to said pinion and arranged to be received between adjacent gear teeth on said pinion as the latter is moved in the direction of the length of its shaft and a latch arranged to engage such groove and hold said drive-shaft against such axial movement until released. 100

4. In a hoisting apparatus, a frame having outwardly extending arms, a winding-shaft mounted in said arms, a gearwheel and winding-drum fixed on said winding-shaft, a brake device on said winding-shaft, a brake-lever on one of said arms for operating said brake device, an axially slideable drive-shaft mounted in said arms and having an annular groove in one end exterior to one of said arms, a pinion fixed on said drive-shaft and arranged to mesh with said gearwheel, a cone fixed on said drive-shaft, and means carried by said lever for engaging said cone and moving said drive-shaft axially, thereby sliding said pinion out of mesh with said gearwheel in the act of applying the brake, fixed means engageable with said pinion to hold the same against rotation, and means to hold said pinion from sliding out of engagement with said means. 115

5. In a hoisting apparatus, a frame having outwardly extending arms, a winding-shaft mounted in said arms, a gearwheel and winding-drum fixed on said winding-shaft, a brake device on said winding-shaft, a 130

brake-lever on one of said arms for operating said brake device, an axially slidable drive-shaft mounted in said arms and having an annular groove in one end exterior to one of said arms, a pinion fixed on said drive-shaft and arranged to mesh with said gearwheel, a cone fixed on said drive-shaft, and means carried by said lever for engaging said cone and moving said drive-shaft 10 axially, thereby sliding said pinion out of mesh with said gearwheel in the act of applying the brake, a latch pivotally mounted on one of said arms and arranged to fall by gravity into engagement with such groove

and hold said drive-shaft against such axial movement, means for limiting the lifting release movement of said latch, and fixed means on the other of said arms to be received between adjacent teeth on said pinion as the latter is moved in the direction 20 of the length of its shaft.

In testimony that I claim the invention above set forth I affix my signature, in presence of two witnesses.

EDWARD PAVELKA.
